UNITED STATES PATENT OFFICE.

QUINCY A. BRACKETT, OF PITTSBURGH, PENNSYLVANIA, ASSIGNOR TO WESTINGHOUSE ELECTRIC & MANUFACTURING COMPANY, A CORPORATION OF PENNSYLVANIA.

GAP IONIZER.

Application filed January 16, 1919. Serial No. 271,492.

To all whom it may concern:

Be it known that I, QUINCY A. BRACKETT, a citizen of the United States, and a resident of Pittsburgh, in the county of Allegheny and State of Pennsylvania, have invented a new and useful Improvement in Gap Ionizers, of which the following is a specification.

My invention relates to electrolytic lighting arresters and particularly to arresters in which electrodes made of a film-forming metal, such as aluminum, are immersed in a suitable electrolyte, and it has for its object to provide a novel device and system whereby the films in such arresters may be reformed.

My invention is particularly adapted for use in connection with lightning arresters constructed in accordance with the disclosure 20 of the copending application on protective devices, Serial No. 216,088, filed by Chester T. Alcutt and assigned to the Westinghouse Electric & Manufacturing Company.

Heretofore, it has been customary to 25 form the films in electrolytic lightning arresters by causing a conducting member to bridge the discharge gap which is usually connected in series with the arresters. Bridging members of this nature are usually 30 mounted on rotatable insulating bases which are very heavy and which require considerable power to move. Also, the fact that the bridging member must be moved some distance from the discharge gap in order 35 to prevent arcing thereto when voltage surges traverse the lines, renders any device for automatically charging the arrester by bridging the discharge gap unwieldly and uncommercial.

40 By my invention, I provide a charging device in which the movable bridging member is eliminated and which is particularly adapted for automatic operation.

Referring to the accompanying drawing, 45 Fig. 1 is a diagrammatic view of a system embodying my invention; Fig. 2 is a similar view showing a slightly different form thereof; Fig. 3 is a partially structural and partially diagrammatic view of a charging 50 device constructed in accordance with my invention and also a system for operating the same; Fig. 4 is a diagrammatic view showing the possibilities of employing my invention in conjunction with the structure of the 55 previously mentioned copending applica-

tion; and Fig. 5 is a partially structural and partially diagrammatic view of an arrester embodying a different form of charging device.

Referring to Fig. 1 of the drawings for 60 a more detailed understanding of my invention, I show a line wire at 7, this wire being connected to a horn-shaped discharge member 8. An opposing horn-gap member 9 is connected to ground at 10 through an 65 electrolytic arrester 11. A small antenna 12 is mounted between the bases of the horns 8 and 9 and is connected to the horn 8 through a current-limiting device 13 and switch 14. The resistor 13 must be of such 70 value that current passing therethrough at normal voltage is very small. Under normal conditions, the switch 14 is open and the antenna 12 assumes the potential of the surrounding electrostatic field, thus causing 75 no disturbance of the electrostatic conditions between the horns 8 and 9.

When it is desired to charge the arrester 11, the switch 14 is closed, thereby causing the antenna 12 to assume substantially the 80 same potential as the horn member 8, thus causing the space between the antenna 12 and the horn member 9 to become ionized. This ionization also extends to the horn member 8, causing a breakdown of the atmosphere and an arc to be established 85 between the horn members 8 and 9, thus causing the current to flow from the line 7 to the horn member 8 to the horn member 9 through the arrester 11 to ground. 90

Fig. 2 is a view similar to Fig. 1 except that a condenser 15 is substituted for the resistor 13. The condenser 15 is of such capacity that, at normal frequency, when the switch 14 is closed, the antenna 12 is 95 raised to substantially the same potential as the horn member 8.

Fig. 3 shows a structure in which the condenser effect is provided by means of a pillar-type insulator 16 upon which the horn member 9 is mounted, said pillar-type insulator comprising a series or column of insulating members separated by conducting supporting members, as is well known in the art. The antenna 12 is connected to the pillar-type insulator through a switch 17 provided with an operating coil 18 connected in an auxiliary circuit 19. When the circuit 19 is energized, the switch 17 is closed, thereby changing the potential of the antenna 12 to 100 105 110

substantially that of the horn member 9. The auxiliary line 19 extends parallel to the main line 7 and is energized only when it is desired to charge the arrester.

5 In Fig. 4, the antenna 12 is connected to the horn member 9 through a condenser 15 and is connected to the horn member 8 through the switch 14, a condenser 20 and an inductive coil 21. When the switch 14 is 10 in its closed position, the arrester is substantially similar to that disclosed in the aforementioned application, which consists essentially of a discharge gap provided with a discharge antenna which is connected to both members of the gap but through dissimilar impedance. At normal frequency, the antenna is at the potential of the surrounding field but differs therefrom at abnormal frequency because of the different 20 distribution of impedance drops. When the potential of the antenna approaches the potential of one of the horn members, the atmosphere surrounding the antenna and the other horn member becomes ionized, resulting in 25 a breakdown between the two horn-gap members. When it is desired to charge the arrester 11, the switch 14 is opened, thus causing the antenna 12 to be raised to the potential of the horn 9 and causing a discharge to flow between the horn gap members 8 and 9 to ground 10 through the arrester 11, as previously described, the discharge forming a current path in shunt relationship to the connection containing the 35 switch.

35 In Fig. 5, I show the horns 8 and 9 provided with spherical surfaces 21, for initial discharge, and mounted on insulators 22 and 23. The horn 9 is connected to line 40 7 and horn 8 to ground through a charging impedance 24 and the electrolytic arrester 11. The antenna 12 is connected to the line 7 through a resistance 25, a switch 26, operated by a clock mechanism 27, and 45 the upper portion of the pillar-type insulator 23 which serves as a condenser. The antenna is also connected to the horn 8 through the lower part of the insulator 23, the electrolytic arrester 11 and the charging 50 resistance 24. It is essential that the impedances of the two sides be substantially the same at normal frequency, so that the antenna 12 will have a potential half-way between the potentials of the horns 8 and 55 9. At predetermined intervals, the clock mechanism 27 operates the switch 26 to break the circuit in which it is connected, and the antenna 12 is immediately raised to substantially the potential of the horn 60 8, causing a breakdown between the horns 8 and 9, in the manner previously pointed out.

65 Although I have shown and described my invention with the antenna located half-way between the horns 8 and 9, it is, of course,

obvious that it could be disposed anywhere between these members, the only essential feature being that the impedances be of such value that the antenna is normally maintained at substantially the same potential 70 as the immediately adjacent electrostatic field at normal frequency.

75 While I have described my invention in connection with electrolytic lightning arrester film-forming devices, I desire it to be understood that it is applicable for use in any device employing a spark gap which is broken down to accomplish some purpose, such, for example, as exploding mines and other similar apparatus operated in this 80 manner.

85 While I have shown my invention in a plurality of forms, it will be obvious to those skilled in the art that it is not so limited but is susceptible of various minor changes and modifications without departing from the spirit thereof and I desire, therefore, that only such limitations shall be placed thereupon as are imposed by the prior art or are set forth in the appended 90 claims.

I claim as my invention:

1. In combination with an electrolytic lightning arrester, a film-forming device comprising two main discharge members 95 rigidly mounted in spaced relation to each other, one of said main discharge members being connected to ground through said electrolytic arrester, and an auxiliary discharge member fixedly mounted adjacent 100 said main discharge members, and means for changing the potential of said auxiliary discharge member to substantially the same value as that of one of the main discharge members.

105 2. In combination with an electrolytic lightning arrester, a film-forming device comprising two main discharge members rigidly mounted in spaced relation to each other, one of said main discharge members being connected to ground through said electrolytic arrester, an auxiliary discharge member fixedly mounted intermediate 110 said main discharge members, and means for changing the potential of said auxiliary discharge member to substantially the same 115 value as that of one of the main discharge members.

3. In combination with an electrolytic lightning arrester, a film-forming device 120 comprising two main discharge members mounted in spaced relation to each other, one of said main discharge members being connected to ground through said electrolytic arrester, and an auxiliary discharge 125 member mounted intermediate said main discharge members and said auxiliary discharge member comprising a condenser and a switch and automatic means for opening and closing said switch.

4. In combination with an electrolytic lightning arrester, a film-forming device comprising two main discharge members mounted in spaced relation to each other, one of said main discharge members being connected to a supply circuit and the other being connected to ground through said electrolytic arrester, and an auxiliary discharge member mounted intermediate said main discharge members, and a connection between one of said main discharge members and said auxiliary discharge member comprising a condenser formed by an insulator on which one of said main discharge members is mounted, and a switch.

5. In combination with an electrolytic lightning arrester, a film-forming device comprising two main discharge members mounted in spaced relation to each other, one of said main discharge members being connected to a supply circuit and the other being connected to ground through said electrolytic arrester, one of said main discharge members being mounted on a pillar-type insulator, and an auxiliary discharge member mounted intermediate said main discharge members and connected to one of the metallic plates of said pillar-type insulator through a switch, and means for automatically opening and closing said switch at predetermined intervals.

6. In combination with an electrolytic lightning arrester, a film-forming device comprising two main discharge members mounted in spaced relation to each other, one of said main discharge members being connected to a supply circuit and the other to ground through said electrolytic arrester, an auxiliary discharge member mounted adjacent said main discharge members, connections embodying impedance members of dissimilar character between said auxiliary discharge member and said main discharge members, respectively, and means for causing the potential of said auxiliary discharge member to be substantially the same as that of one of the main discharge members.

7. In combination with an electrolytic lightning arrester, a film-forming device comprising two main discharge members mounted in spaced relation to each other, one of said main discharge members being connected to a supply circuit and the other to ground through said electrolytic arrester, an auxiliary discharge member mounted adjacent said main discharge members, connections embodying impedance members of dissimilar character between said auxiliary discharge member and said main discharge members, respectively, and a switch connected in the circuit between said auxiliary discharge member and one of said main discharge members.

8. In combination with an electrolytic lightning arrester, a film-forming device

comprising two main discharge members mounted in spaced relation to each other, one of said main discharge members being connected to a supply circuit and the other to ground through said electrolytic arrester, an auxiliary discharge member mounted adjacent said main discharge members, and means whereby, at normal frequency of said circuit, said auxiliary electrode is maintained at substantially the potential of the immediately adjacent electrostatic field set up by said discharge members, and additional means whereby said auxiliary electrode may be charged to disturb said electrostatic field.

9. In combination with an electrolytic lightning arrester, a film-forming device comprising two main discharge members mounted in spaced relation to each other, one of said main discharge members being connected to a supply circuit and the other to ground through said electrolytic arrester, an auxiliary discharge member mounted adjacent said main discharge members, and means whereby at normal frequency of said circuit, said auxiliary electrode is maintained at substantially the potential of the immediately adjacent electrostatic field set up by said discharge members, and additional means whereby said balanced condition may be destroyed.

10. In a discharge-gap device comprising two spaced main electrodes maintained at different potentials and an intermediately disposed auxiliary electrode connected by shunt connections to said main electrodes, the method of effecting a breakdown between said main electrodes comprising increasing the impedance of the shunt connection between said auxiliary electrode and one of said main electrodes, whereby the potential of said auxiliary electrode is changed.

11. In a discharge-gap device comprising two main electrodes spaced apart to form a gap and maintained at different potentials, and an intermediately disposed auxiliary electrode connected to said main electrodes by connections disposed in shunt relationship to said gap, the method of effecting a breakdown between said main electrodes comprising causing an arc between said auxiliary electrode and one of said main electrodes, whereby the potential of said auxiliary electrode is changed.

12. In a discharge-gap device comprising two main electrodes spaced apart to form a gap and maintained at different potentials, and an intermediately disposed auxiliary electrode connected to said main electrodes by connections disposed in shunt relationship to said gap, said shunt connection comprising a switch, the method of effecting a breakdown between said main electrodes comprising opening said switch sufficiently to draw an arc between some of said elec-

trodes, whereby the potential of said auxiliary electrode is changed.

13. The combination with two fixed discharge gap members, spaced apart to form a gap, one of which is connected to a supply circuit and the other of which is connected to ground, an auxiliary discharge member disposed intermediate said main discharge members, of means connected to both of said discharge-gap members constituting a shunt connection to said gap and comprising a plurality of impedance members of dissimilar nature and a switch, said auxiliary discharge member being connected to said shunt connection at a point the potential of which corresponds to the potential of the electrostatic field immediately adjacent the auxiliary discharge member.
14. The combination with two fixed discharge-gap members spaced apart to form a

gap, one of which is connected to a supply circuit and the other of which is connected to ground, an auxiliary discharge member disposed intermediate said main discharge members, of means connected to both of said discharge-gap members constituting a shunt connection to said gap and comprising a plurality of impedance members of dissimilar nature and a switch, said auxiliary discharge member being connected to said shunt connection at a point the potential of which corresponds to the potential of the electrostatic field immediately adjacent the auxiliary discharge member and means for opening said switch to alter the potential of said auxiliary discharge member.

In testimony whereof I have hereunto subscribed my name this 30th day of December, 1918.

QUINCY A. BRACKETT.
